COAL CUTTING, DRILLING, AND LOADING MACHINE

Ross H. Goodrich, Claremont, N.H., assignor to Joy Manufacturing Company, Pittsburgh, Pa., a corporation of Pennsylvania

Filed May 31, 1956, Ser. No. 588,473

14 Claims. (Cl. 262—9)

This invention relates to a mining apparatus and more particularly to a combined cutting, drilling and loading machine whereby a self-contained unitary structure may replace separate cutting, drilling and loading units.

In the mining of mineral such as coal, the coal is usually cut by a kerf cutting machine which may cut one or more slots or kerfs in the solid coal. Thereafter the coal is drilled by a separate blast hole drilling machine and blasted down in a conventional manner. Then a loading machine is brought up to the face and the shot-down coal is loaded out. The present invention contemplates improvements over previous cutting, drilling and loading machines in that the cutting, drilling and loading functions are effected by a self-contained unit involving smaller original outlay in equipment and reducing the cost of maintenance, resulting in the production of coal in an efficient and a more economical manner.

An object of the present invention is to provide an improved mining apparatus. Another object is to provide an improved self-contained coal mining apparatus having cutting, drilling and loading functions. A further object is to provide an improved combined cutting, drilling and loading apparatus mounted on a mobile base and embodying elements common to the cutting, drilling and loading functions of the machine. A still further object is to provide an improved cutting and loading machine wherein the kerf cutter may act as a gathering bar and cooperates with a conveyor in the loading of loose coal at the face. Yet another object is to provide an improved kerf cutting machine of the universally adjustable cutter bar type having conveying means associated therewith to provide a self-contained cutting and loading unit wherein the cutter bar is operable not only to cut the coal but also may act as a gathering bar to load the loose coal onto the conveying means. A still further object is to provide an improved conveying means having an adjustable forward receiving portion which may be retracted from the face during the cutting operation and may be extended toward the face during the loading operation. Another object is to provide an adjustable kerf cutting means having its cutter bar adjustable to serve as a gathering bar to gather loose coal on the mine floor and move it laterally to the receiving portion of the conveying means. A still further object is to provide an improved unitary cutting, drilling and loading machine wherein the parts cooperate in a novel manner to effect cutting, drilling and loading of coal. Other objects and advantages of the invention will, however, hereinafter more fully appear.

In the accompanying drawings there is shown for purposes of illustration one form which the invention may assume in practice.

In these drawings:

Fig. 1 is a plan view of the improved unitary cutting, drilling and loading machine, with the kerf cutting mechanism, drilling mechanism and conveying means disposed in trammimg position.

Fig. 2 is a side view of the machine shown in Fig. 1

2

with the cutter bar lowered to the mine floor and different positions of the drill indicated in full and dotted lines.

Fig. 3 is an enlarged fragmentary plan view of the kerf cutting mechanism.

5 Fig. 4 is a side view of the kerf cutting mechanism shown in Fig. 3.

Figs. 5 and 5^a, taken together, are an enlarged longitudinal vertical section taken on line 5—5^a of Fig. 1, showing the front receiving portion of the conveyor in raised 10 tilted position.

Figs. 6 and 6^a, taken together, are an enlarged longitudinal vertical section taken on line 6—6^a of Fig. 1, showing the receiving portion of the conveyor lowered to the mine floor.

15 Fig. 7 is a cross section taken on line 7—7 of Fig. 5.

Fig. 8 is a cross section taken on line 8—8 of Fig. 6^a.

Fig. 9 is an enlarged longitudinal vertical section taken on line 9—9 of Fig. 1, showing the swivelled drill mounting.

20 Fig. 10 is a horizontal section taken on line 10—10 of Fig. 9.

Fig. 11 is a schematic view showing the hydraulic fluid system.

Figs. 12 to 15 inclusive are diagrammatic views showing the machine in its different operating positions in an 25 underground mine.

The improved combined cutting, drilling and loading machine generally comprises a mobile base 1 carrying an adjustable kerf cutting mechanism generally designated

30 2, an adjustable drilling mechanism generally designated 3, and a loading mechanism generally designated 4.

The mobile base 1 may assume various forms but herein, for illustrative purposes, may be similar to that 35 disclosed in the Baldwin et al. Patent No. 2,562,881, dated August 7, 1951, also owned by the assignee of the present invention, and the kerf cutting mechanism 2 mounted on the base likewise, for illustrative purposes, may be similar to that of this patent. The mobile base includes a 40 frame 5 mounted on rubber-tired steering and traction wheels 6 and 7, although evidently, if desired, the base frame may be mounted in other conventional manners as on crawler treads or track engaging wheels.

The base frame carries a motor 8, desirably an electric motor, to which motive power may be conducted 45 through a power conductor cable 9 wound on an automatic cable reel mechanism 10. The motor 8 drives the front traction wheels 7 and a pumping means 11 for supplying liquid under pressure to the various hydraulically operated devices of the machine.

50 The kerf cutting mechanism 2 may assume various forms but herein, as shown specifically in Figs. 3 and 4, comprises a horizontal turntable 12 on which is pivotally mounted to swing vertically a boom frame 13 carrying a cutter head 14 rotatable about the longitudinal axis of the boom frame. Pivotally mounted at 15 on the rotatable head is a tilttable support 16 on which is swivelly mounted an elongated plane cutter bar 17 about the margin of which an endless cutter chain 18 is guided for orbital circulation. A motor 19, desirably an electric motor, is carried by the rearward portion of the boom frame for driving the cutter chain and power medium may be supplied to this motor through the conductor cable 9. Hydraulic cylinders 20 serve to tilt the boom frame in a vertical direction relative to the turntable about a horizontal pivot shaft 20' while a hydraulic cylinder 21 serves to tilt the support 16 about its pivot relative to the rotatable head. A pair of hydraulic cylinders 22 serve to swing the cutter bar about its pivot relative to the tilttable support 16 while a conventional reversible hydraulic motor 23 serves to rotate the head about the longitudinal axis of the boom frame. The

3

turntable 12 may be rotated relative to the base frame by a similar reversible hydraulic motor 24 (Fig. 11). From the foregoing it will be evident that the cutter bar 17 may be adjusted to cut kerfs in the solid mineral of a mine vein in horizontal planes at any desired location between the mine floor and roof and to cut vertical shear-kerfs at any desired location between the ribs, as is fully disclosed in the Baldwin et al. patent above referred to.

Now referring to the drilling mechanism 3, which may assume various forms, it will be observed that mounted on the machine-base rearwardly of the kerf cutting mechanism 2 is a swivelled frame 25 turnable about a vertical axis relative to the base-frame and pivotally mounted at 26 on the swivelled frame is a vertically swingable boom frame 27 which carries a rotatable support 28 arranged with its axis of rotation extending generally lengthwise of the boom frame. Swingably mounted at the outer portion of the swivelled support is a yoke frame 29 on which is tiltably mounted at 30 an elongated drill guide frame 31 extending forwardly above the kerf cutting mechanism, as shown in Fig. 2.

A rotary drilling tool 32 is guided for rectilinear back and forth movements along the guide frame and this drilling tool has a hydraulic motor 33 for rotating an auger drill steel 34 which carries an auger drill bit 35. A conventional reversible hydraulic motor 36 serves to feed the drilling tool along the guide frame while a hydraulic cylinder 37 serves to tilt the guide frame about its pivot relative to the yoke frame 29. Hydraulic cylinders 38 serve to swing the yoke frame on its swivel relative to the rotatable support 28 and the latter may be rotated by a conventional reversible hydraulic motor 39. The hydraulic cylinder 40 serves to swing the boom frame vertically about its pivot relative to the swivelled frame 25 while a hydraulic cylinder 41 serves to turn the swivelled frame 25 about its vertical axis.

In Fig. 9 the swivelled frame 25 is shown mounted on bearings 42 supported by a vertical pivot shaft 43 carried by a suitably braced bracket 44. The boom frame pivot is provided by a transverse pivot shaft 45 and the hydraulic cylinder 40 is pivotally mounted at 46 on the boom frame and contains a reciprocable piston 47 having its piston rod 48 pivotally connected at 49 to the upper portion of the swivelled frame 25. As shown in Fig. 10 the swivelled frame 25 may be turned horizontally about the vertical pivot shaft 43 by the hydraulic cylinder 41 pivotally mounted at 50 on the base frame and containing a reciprocable piston 51 having its piston rod 52 connected at 53 to a reciprocable rack 54 guided along a guideway 55. The teeth of this rack engage the teeth of a gear segment 56 secured to the swivelled frame 25. It will thus be seen that the drilling tool may be adjusted through a wide range of drilling positions with respect to the machine base, thereby to enable drilling of blast holes in the coal face at various locations between the mine roof and floor and between the ribs.

The loading mechanism 4 is supported on lateral armlike supports 58 and 59 at one side of the mobile base (Fig. 1) and comprises a front elevating conveyor 60 and a rear discharge conveyor 61. These conveyors have superimposed overlapping portions, shown in Fig. 5, and the rear conveyor has a frame 62 secured to the armlike supports 58 and 59 and provides a longitudinal guideway 63 along which a frame 64 of the front conveyor is guided for rectilinear movement longitudinally of the machine base. The overlapping portions of the conveyors enable the front conveyor to discharge onto the rear conveyor irrespective of the position of the front conveyor relative to the rear conveyor. The slideable frame 64 of the front conveyor has a tiltable forward portion 65 pivoted at 66 and hydraulic cylinders 67 serve to tilt the forward conveyor portion between a position at the floor level (Fig. 6a) and a raised inclined position off the floor (Fig. 5a). Guided for

orbital circulation relative to the front conveyor frame 64 is an endless conveyor chain 68 having lateral flights 69 which move the loose coal being conveyed along a bottom plate 70 of a troughlike upper portion 71. The rear conveyor comprises an endless conveyor chain 72 having lateral flights 73 which move along a bottom plate 74 of a troughlike upper frame portion 75. An inclined ramp 76 (Figs. 6a and 8) is provided at the inner side of the forward tiltable portion of the front conveyor, and loose coal may be moved from the mine floor up along this ramp onto the forward receiving portion of the front conveyor in a manner to be later explained. The front end of the conveyor frame is similarly inclined at 77 to facilitate penetration of the loose coal as the front conveyor is extended toward the coal face. Hydraulic cylinders 78 (Figs. 1, 6 and 7) are secured to the sides of the rear conveyor frame and contain reciprocable pistons 79 having their piston rods 80 attached at 81 to brackets 82 secured to the sides of the slideable front conveyor frame 64, whereby the front conveyor may be slid back and forth for retraction from or extension toward the working face of the coal seam.

The front conveyor chain may be driven by a motor 83, desirably an electric motor, and similar motors 84 serve to drive the rear conveyor chain, in conventional manners. Here, too, power medium may be conducted to these electric motors through the power conductor cable 9. A hydraulic cylinder 85 serves to tilt the rearward portion of the rear conveyor and the rearward portion of the rear conveyor may be swung horizontally by hydraulic cylinders 86 (Figs. 5 and 11). The outer front end of the front conveyor frame may have a curved abutment member 87 which may engage with a rib near the coal face.

As shown schematically in Fig. 11 the pumping means 11, which may assume any conventional form, has its suction side connected by a conduit 89 connected to a liquid tank 90 carried on the machine base and the discharge side of the pumping means is connected by a conduit 91 to the pressure passage of a valve box 92 of a conventional control valve mechanism likewise carried on the machine base. The discharge passage of the valve box is connected by a conduit 93 back to the tank. The valve box is desirably made up of sections having bores for receiving conventional spool type slide valves 94, 95, 96, 97, 98, 99, 100, 101, 102 and 103, each having an operating handle. The bore containing the slide valve 94 is connected by conduits 104 and 105 to the motor 24 for rotating the turntable 12, while the bore containing the slide valve 95 is connected by a conduit 106 to the boom tilt cylinders 20. The bore containing the slide valve 96 is connected by conduits 107 and 108 to the motor 23 for rotating the cutter head, while the bore containing the slide valve 97 is connected through conduits 109 and 110 to the opposite ends of the tilt cylinder 37. The bore containing the slide valve 98 is connected by conduits 111 and 112 to the opposite ends of the swing cylinders 22 for the cutter bar, while the bore containing the slide valve 99 is connected by conduits 113 and 114 to the opposite ends of the tilt cylinder 85 for the rear conveyor. The bore containing the slide valve 100 is connected by conduits 115 and 116 to the opposite ends of the cylinder 41 for horizontally swinging the drill boom frame, while the bore containing the slide valve 101 is connected by conduit 117 to the tilt cylinder 40 for the drill boom frame. The bore containing the slide valve 102 is connected by conduits 118 and 119 to the opposite ends of cylinders 78 for sliding the front conveyor, while the bore containing the slide valve 103 is connected by a conduit 120 to the tilt cylinders 67 for the front receiving portion of the conveyor. The cylinders 22, 37, 41, 78 and 85 are double acting and their respective slide valves may be positioned to trap fluid therein to hold the parts moved thereby in adjusted position.

Referring to the diagrammatic views of Figs. 12 to 15 inclusive the general mode of operation of the improved cutting, drilling and loading machine will now be described. In Fig. 12 the front conveyor and the drilling tool are in retracted positions on the machine-base and the cutter bar of the kerf cutting mechanism is disposed at the floor level in horizontally sumped position at the right-hand rib. At this time, as shown, the machine is angled slightly with respect to the ribs and the curved abutment 87 at the front end of the front conveyor frame is disposed against the left-hand rib. When the machine is so positioned the forward receiving portion of the conveying means is in its upwardly tilted position, as shown in Fig. 5^a, so that the outer portion of the cutter bar may move beneath the same as it is swung horizontally, by rotation of the turntable 12, across the coal face to form a horizontal slot or kerf in the coal at the floor level. By rotating the cutter head 14 the cutter bar may be disposed in a vertical shearing position to cut a vertical kerf in the coal, in a well-known manner, and during either the horizontal or vertical cutting operation the cutter bar may be swung about its pivot by the swing cylinders 22 to change its angular position as desired. The mode of operation of the coal cutting machine is fully disclosed in the above mentioned Baldwin et al. patent and therefore further detailed description thereof is herein unnecessary.

Upon completion of the kerf cutting operation the drill boom frame may be adjusted by suitable operation of the swing cylinders 40 and 41 to bring the drilling tool into the desired drilling position with respect to the coal face, as shown in Fig. 13, and blast holes may be drilled, and upon completion of drilling the machine may be retracted from the face as shown in Fig. 14, and the cut coal may be blasted from the face as shown.

The machine may then again be brought up near the face as shown in Fig. 15, and the hydraulic cylinder 78 may be operated to extend the front conveyor to bring its lowered receiving portion beneath the shot-down coal up close to the face at the left hand rib. The cutter bar may then be brought into the substantially vertical edge-wise position shown and by swinging the boom frame 13 horizontally the cutter bar may act as a gathering bar to gather the loose coal on the mine floor and move it laterally toward and up the ramp 76 onto the front conveyor which conveys the coal rearwardly to discharge onto the rear conveyor, the latter in turn moving the coal rearwardly to a convenient point of discharge as for example into a shuttle car, onto a conveyor or other receiving means. Under certain conditions, the cutter bar when in horizontal position may penetrate beneath large blocks of standing coal and lift and move laterally the block of coal onto the front conveyor. Also the cutter bar may disintegrate blocks of coal which are too large for handling by the conveying means.

As a result of this invention an improved combined cutting, drilling and loading machine is provided whereby the coal may be economically and efficiently mined out. By mounting the cutting, drilling and loading mechanisms on a common mobile base, elements common to the cutting, drilling and loading functions may be provided thereby substantially reducing the cost which would be necessary if separate cutting, drilling and loading units were employed. By utilizing the cutter bar as a gathering bar for moving the loose coal on the mine floor laterally toward the front conveyor the gathering operation is greatly simplified, and any need for separate gathering means is eliminated. The unitary cutting, drilling and loading machine is not only economical in operation but is also relatively rugged and compact in design, well adapted for use in the mining of coal in an underground mine. Other advantages of the invention will be clearly apparent to those skilled in the art.

While there is in this application specifically described one form which the invention may assume in practice, it

will be understood that this form of the same is shown for purposes of illustration and that the invention may be modified and embodied in various other forms without departing from its spirit or the scope of the appended claims.

What I claim as new and desire to secure by Letters Patent is:

1. In combination, a mobile base, kerf cutting mechanism mounted on said base for movement relative thereto to effect cutting of plane kerfs in the solid mineral of a mine vein, drilling mechanism adjustably mounted on said base rearwardly of the effective cutting portion of said kerf cutting mechanism and extending above the latter for drilling blast holes in the mineral at various locations in the face, and loading mechanism mounted on said base longitudinally at one side of said base and laterally of said kerf cutting and drilling mechanisms, said loading mechanism having a forward receiving conveyor portion disposed at the floor level, and, said kerf cutting mechanism being positionable and operable to effect its kerf cutting operation by movement relative to said drilling and loading mechanisms, and said drilling and loading mechanisms positionable while mountably retained on said base to permit such operation of said kerf cutting mechanism during cutting.
2. A combination as set forth in claim 1 wherein said loading means has a conveyor which provides said forward receiving portion, and means is provided on said base for extending and retracting said forward conveyor portion with respect to said base.
3. A combination as set forth in claim 1 wherein said loading mechanism includes a conveyor having a tiltable forward receiving portion disposable at the floor level, and means is provided on said base for tilting said forward receiving portion to provide a space therebeneath, and said kerf cutting mechanism includes a horizontally movable kerf cutter movable into the space beneath said conveyor portion during the kerf cutting operation.
4. A cutting and loading machine comprising a mobile base, kerf cutting mechanism mounted on said base for movement relative thereto including an adjustable plane kerf cutter for cutting plane kerfs in the solid mineral of a mine vein either horizontally or vertically, and loading mechanism carried by said base at one side of the latter and having a forward receiving portion disposable at the floor level, and means for operating said kerf cutter to move its plane side into engagement with the dislodged mineral for moving the latter laterally from the mine floor towards and onto said forward receiving portion of said loading mechanism.
5. A cutting and loading machine as set forth in claim 4 wherein the forward receiving portion of said loading mechanism is extendible and retractible with respect to said base, and means is provided on said base for extending and retracting said forward receiving portion of said loading mechanism.
6. A cutting and loading machine as set forth in claim 4 wherein means is provided for adjusting said forward receiving portion of said loading mechanism vertically to provide a space therebeneath for receiving the outer portion of said kerf cutter during a portion of the horizontal movement of said kerf cutter as the latter effects its horizontal kerf cutting operation.
7. A cutting and loading machine as set forth in claim 5 wherein said forward receiving portion of said loading mechanism has a front penetrating end for penetrating the dislodged mineral on the mine floor when said receiving portion is extended toward the mine face.
8. A cutting and loading machine as set forth in claim 7 wherein said forward receiving portion of said loading mechanism has a lateral receiving portion for receiving the dislodged mineral as the latter is moved laterally toward said loading mechanism.
9. In combination, a base movable over the floor of

a mine, kerf cutting mechanism mounted on said base for movement relative thereto including a horizontally swingable kerf cutter for cutting a plane kerf in the solid mineral of a mine vein, loading mechanism carried by said base for receiving the dislodged mineral, and means for operating said kerf cutter to move the plane side of said kerf cutter into engagement with the dislodged mineral to move the latter laterally onto said loading mechanism.

10. In combination, a mobile base movable over the floor of a mine, kerf cutting mechanism carried by said base for movement relative thereto to effect cutting of plane kerfs in the solid mineral of a mine vein, drilling mechanism adjustably mounted on said base for drilling blast holes in the solid mineral at various locations, loading mechanism on said base longitudinally at one side of said kerf cutting and drilling mechanisms for loading out the dislodged mineral, means for adjusting said kerf cutting mechanism laterally toward one rib relative to said loading mechanism while the latter is disposed at the opposite rib, and means for adjusting said drilling mechanism for movement relative to said base and to said kerf cutting mechanism into various drilling positions including a drilling position in the space between said kerf cutting mechanism and said loading mechanism.

11. In combination, a mobile base, kerf cutting mechanism mounted on said base for movement relative thereto to effect cutting of plane kerfs in the solid mineral of a mine vein and including an elongated cutter supporting frame structure extending longitudinally of said base in advance of the latter, a drilling mechanism adjustably mounted on said base and including an elongated drill supporting frame structure extending longitudinally of said base in advance of the latter in superimposed relation with respect to said cutter supporting frame structure, and loading mechanism mounted on said base and including a frame structure extending longitudinally in advance of said base along one side of the latter and said cutter supporting frame structure and, said kerf cutting mechanism being positionable and operable to effect its kerf cutting operation by movement relative to said drilling and loading mechanisms, and said drilling and loading mechanisms positionable while mountably retained on said base to permit such operation of said kerf cutting mechanism during cutting.

12. A combination as set forth in claim 11 wherein said cutter supporting frame structure, said drill supporting frame structure and said frame structure of said loading mechanism each has a tiltable forward portion whereby the forward ends thereof may be elevated with respect to said base.

13. A combination as set forth in claim 11 wherein the forward longitudinal projection of said drilling mechanism in advance of said base is substantially coextensive with the longitudinal forward projection of said loading mechanism.

14. In combination, a base movable over the floor of a mine, loading mechanism carried by said base longitudinally at one side of the latter and having a forward receiving portion disposable at the floor level but near the mine-face, gathering means carried by said base comprising an adjustable relatively narrow elongated gathering bar having a plane upright surface for engaging loose mineral on the mine floor and for moving the mineral laterally toward said receiving portion of said loading mechanism, and means mounted on said base for adjustment relative thereto and by which said gathering bar is supported for translatory movement over the floor above the latter for adjusting and moving said gathering bar; said adjusting and moving means for said gathering bar includes means for swinging said bar to move the upright plane surface horizontally relative to said base near the floor level about parallel vertical axes.

15

20

15. In combination, a base movable over the floor of a mine, loading mechanism carried by said base longitudinally at one side of the latter and having a forward receiving portion disposable at the floor level but near the mine-face, gathering means carried by said base comprising an adjustable relatively narrow elongated gathering bar having a plane upright surface for engaging loose mineral on the mine floor and for moving the mineral laterally toward said receiving portion of said loading mechanism, and means mounted on said base for adjustment relative thereto and by which said gathering bar is supported for translatory movement over the floor above the latter for adjusting and moving said gathering bar; said adjusting and moving means for said gathering bar includes means for swinging said bar to move the upright plane surface horizontally relative to said base near the floor level about parallel vertical axes.

25

20. In combination, a base movable over the floor of a mine, loading mechanism carried by said base longitudinally at one side of the latter and having a forward receiving portion disposable at the floor level but near the mine-face, gathering means carried by said base comprising an adjustable relatively narrow elongated gathering bar having a plane upright surface for engaging loose mineral on the mine floor and for moving the mineral laterally toward said receiving portion of said loading mechanism, and means mounted on said base for adjustment relative thereto and by which said gathering bar is supported for translatory movement over the floor above the latter for adjusting and moving said gathering bar; said adjusting and moving means for said gathering bar includes means for swinging said bar to move the upright plane surface horizontally relative to said base near the floor level about parallel vertical axes.
